UNITED STATES PATENT OFFICE.

WILLIAM FEHR, OF PHILADELPHIA, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

METAL-SWAGING MACHINE.

No. 877,815.

Specification of Letters Patent.

Patented Jan. 21, 1908.

Original application filed December 22, 1905, Serial No. 292,946. Divided and this application filed November 26, 1906, Serial No. 345,020. Renewed October 21, 1907. Serial No. 398,504.

To all whom it may concern:

Be it known that I, WILLIAM FEHR, a citizen of the United States, residing at the city of Philadelphia, in the county of Philadelphia and State of Pennsylvania, have invented certain new and useful Improvements in Metal-Swaging Machines, of which the following is a specification.

My invention has relation to a swaging machine; and in such connection it relates particularly to the construction and arrangement of such a machine and being a division of an application filed by me under date of December 22nd, 1905, Serial No. 292,946.

15 The principal objects of my invention are first, to provide a metal swaging machine with means to swage or spread metal strips or wires such as are used in the manufacture of heddles either at the ends of slots punched 20 to expand the same into eyes and mortises of required width or to expand the metal strip or wire into the required width of mortises and eyes prior to the slotting or piercing thereof; second, to provide the swaging machine with a hammer of a weight sufficient when descending by gravity to deliver a blow to permit a tool carried by the hammer in conjunction with a second tool held in a fixed position to expand or spread the metal 25 30 to the width required; third, to provide the swaging machine with means to limit the movement of the hammer so as to control the extent of the swaging of the metal; and fourth, to provide the swaging machine with 35 means to guide the metal strip or wire so as to insure the swaging of the same in the longitudinal central axis thereof.

The nature and scope of my invention will be more fully understood from the following 40 description, taken in connection with the accompanying drawings forming part hereof, in which

Figure 1, is a view, illustrating in side elevation a swaging machine, having a swaging 45 hammer, means for raising the hammer and permitting the same to descend by gravity, means for actuating the raising means of the hammer, means for limiting the downward movement of the hammer and guiding 50 means for a metal strip or wire, all embodying features of my invention. Fig. 2, is a front elevational view of the machine. Fig. 3, is a view illustrating the machine in longitudinal central section. Figs. 4 and 5 are

views illustrating respectively, in longitudinal section and in top or plan view a guide for the metal strip to be swaged. Figs. 6 and 7 are similar views illustrating respectively, in front elevation and in cross-section swaging or expanding tools used in conjunction with a portion of the swaging machine supporting the same. Fig. 8, is a view illustrating in section means for limiting the downward movement of the swaging hammer, and Figs. 9 and 10, are views, enlarged, 65 illustrating in elevation the metal strip prior to and after the swaging operation.

Referring to the drawings *g*, is a support or bed-plate, to which by means of a threaded bolt *g*³, is removably secured the swaging tool *g*¹, forming an anvil for the metal strip *b*, which is fed forward by mechanism, not shown. By this forward movement the metal strip *b*, is brought with a slot previously formed directly above the tool *g*¹. Above *g*¹, and held in alinement with the same by a support *g*⁴, is arranged a second tool *g*², forming in conjunction with the support *g*⁴, a hammer which delivers the blow necessary to expand the metal strip in the present instance at the respective ends of slots *b*¹ and *b*². By spreading the metal at these points, the slots formerly oblong in outline, as shown in Fig. 9, are now transformed into slots of oval outline, each having at its respective ends a rib-like portion *b*³, as shown in Fig. 10. In order to form these rib-like portions *b*³, each of the tools *g*¹ and *g*², taper as at *g*⁴, towards their free ends and are slightly curved at the same to form when the tools contact with each other abutting portions *g*⁵, and by their outwardly flaring portions *g*⁶, wedge shape indentations *g*⁷, which permit of the formation of the rib. The metal of the strip *b*, is compressed by the flaring portions *g*⁶, of the tools *g*¹ and *g*², which thus form at the ends of the respective slots *b*¹ and *b*², the rib-like projections *b*³, which correspond in cross-section with the outline of the wedge-shape indentations *g*⁷, formed by the tools. Thus the degree of compression of the metal is the greatest at the point where the same is directly brought into engagement with cross-bars of a heddle frame passing through the mortises *b*¹. It follows therefore, that the swaged portion *b*³, of the metal strip *b*, forms a reinforcement of the same at the point of greatest wear, which also prevents

the tearing of the metal at the ends of the slots otherwise occurring when the metal is not strengthened in the manner hereinbefore described. The upper tool g^2 , by means of a threaded bolt g^8 , is removably secured to the support g^4 , which is of sufficient weight when raised and released and permitted to descend by gravity to produce the necessary force to compress and spread the metal held in position between the tools g^1 and g^2 , and thereby to expand the narrow slots b^1 and b^2 , in the strip b , into mortises and an eye of the required width. The means for raising and then permitting the hammer g^4 , to drop, consists of bell-crank lever g^9 , pivotally secured to the point g^{10} , to a bracket g^{12} , formed integral with the support g , and bearing with its arm g^{11} , against a projection g^{13} , of the hammer g^4 . The projection g^{13} , in the point g^{14} , is pivotally secured to a bracket g^{15} , formed integral with the support g , and thus the hammer support g^4 , has a range of oscillating movement in the bracket g^{15} , which is imparted to the same in an upward direction by a cam a^4 , secured to 25 a driving shaft a^1 , and engaging a roller g^{16} , of the lever g^9 , in a downward direction by gravity, as soon as the roller g^{16} , leaves the highest part a^5 , of the throw portion of the cam a^4 , as shown in Fig. 1. However, the downward movement of the support g^4 , and its tool g^2 , forming a hammer is limited by a threaded bolt g^{17} , abutting with its lower end against a bolt g^{18} , arranged in the support g , of the swaging mechanism, as shown in Figs. 1 and 30 3 and 8. Thus the downward movement of the tool g^2 , is limited at the moment its portion g^6 , is brought in proximity with the portion g^5 , of the tool g^1 .

In order to insure the swaging of the metal strip b , at the ends of the slots b^1 and b^2 , and in the longitudinal central axis of the same, the metal strip is conducted through guides g^{19} , arranged at each side of the tools g^1 and g^2 , as shown in Fig. 2. Each of the guides g^{19} , consists preferably of a bar g^{20} , adjustably secured to the support g . The bar g^{20} , is provided with an adjustable guide g^{21} , extending in the path of the metal strip b , and forming a rigid guide for the same. Opposite the guide g^{21} , and limited in its movement by a projection g^{25} , of a plate g^{24} , secured to the bar g^{20} , is arranged a yielding guide, consisting of a leaf-spring g^{22} , abutting with its downward projecting end g^{23} , against the strip b , as shown in Fig. 4. At its lower end the bar g^{20} , is preferably secured to the support g , as shown in Figs. 1 and 2. Thus the guide g^{22} , by yielding enables portions of the metal strip b , differing in width to readily pass between the guides g^{21} and g^{22} . In this manner the metal strip b , is prevented from jamming between these guides and is held by the same irrespective of varying width, in a position

which insures the swaging of the strip in the longitudinal central axis thereof.

Instead of swaging the metal strip b , after the punching of the slots b^1 and b^2 , therein, the swaging of the same may take place prior to the punching of the slots. This swaging prior to the punching is necessary, when a wire in place of a flat narrow strip of metal is employed to form the heddles. In this instance, the wire has first to be flattened by the tools g^1 and g^2 , at the portions in which the mortises and eyes are to be formed to spread or expand the same to the required width.

Having thus described the nature and objects of my invention, what I claim as new and desire to secure by Letters Patent is:—

1. In a machine of the character described, a support having a tool forming an anvil, a second support having a tool forming a hammer at one side and a depending projection at the other side and pivotally supported at a point between the hammer and projection and in proximity to the pivot by said first support, a bell crank lever pivotally connected with said first support and contacting with said projection, a cam having an inclined throw portion and a depression, means carried by said lever and contacting with said cam, said cam and means coöperating to impart to said lever and by the same to said second support and its tool a gradual upward movement and to permit of a quick descent by gravity when said means descend into the depression of said cam to form in a metal strip passing between the tools, depressions from opposite sides thereof.

2. In a machine of the character described, a support having a tool forming an anvil, a second support having a tool forming a hammer pivotally supported by said first support, and a depending portion on the side of the pivot opposite the hammer, a bell crank lever pivotally connected with said first support and contacting with said projection, a cam having a gradually inclined throw portion and a depression, and a roller carried by said lever and contacting with said cam, said cam and roller coöperating to impart to said lever and by the same to said second support and its tool a gradual upward movement and to permit of a quick descent by gravity when the roller descends into the depression of said cam to swage the slotted end portions of a metal strip passing between the tools from opposite sides thereof.

In witness whereof, I have hereunto affixed my signature in the presence of two subscribing witnesses.

WILLIAM FEHR.
